UNITED STATES PATENT OFFICE.

JOHN CALVIN LITZELLE, OF ROCKFORD, ILLINOIS.

DESIGN FOR A MUSICAL INSTRUMENT.

SPECIFICATION forming part of Design No. 20,998, dated August 18, 1891.

Application filed June 15, 1891. Serial No. 396,377. Term of patent 14 years.

To all whom it may concern:

Be it known that I, JOHN CALVIN LITZELLE, a citizen of the United States, residing at Rockford, in the county of Winnebago and State of Illinois, have invented and produced a new and original Design for a Musical Instrument; and I do hereby declare the following to be a full, clear, and exact description of the same, reference being had to the accompanying drawing, forming a part thereof.

In the drawing the figure is a perspective view of my newly-designed musical instrument, otherwise called a "toy chuckoo."

The body 1 of the instrument is approximately ovoid in form. The end or mouth-piece 2 is contracted at the sides thereof, and at 3, just in front of the vent 4, it is raised slightly above the level of the body. On the under side, below the mouth, it is curved downwardly at 5, but less abruptly than at the sides of the body. At the opposite end, and just beyond the flute-holes 6, the body contracts rapidly and has an upwardly-curved terminal 7, extending above the general level 25 of the toy. The general appearance of this

part of the design is something like that of a bird.

8 denotes a circular pedestal having a similarly-formed foot 9. The pedestal is curved in vertical planes, and the curves disappear 30 in those of the body and foot, as shown.

It is characteristic of the design that it has the general appearance represented, having the slightly-raised mouth-piece or head 2 at one end and at its opposite end the upwardly-curved terminal or tail, the body being supported upon a pedestal and base, the general outlines and curves being of the character represented.

I claim—

The design for a musical instrument herein shown and described, consisting of the ovoid body 1, the raised head 2, the upwardly and laterally curved terminal, and the pedestal.

In testimony whereof I affix my signature in 45 presence of two witnesses.

JOHN CALVIN LITZELLE.
